UNITED STATES PATENT OFFICE

128,249

DESIGN FOR A COMBINED SOLE AND HEEL

Charles C. Abbott, Auburn, Maine, assignor to Charles Cushman Company, Auburn, Maine, a corporation of Maine

Application January 27, 1941, Serial No. 98,405

Term of patent 3½ years

To all whom it may concern:

Be it known that I, Charles C. Abbott, a citizen of the United States, residing at Auburn, county of Androscoggin, State of Maine, have invented a new, original, and ornamental Design for a Combined Sole and Heel, of which the following is a specification, reference being had to the accompanying drawing, forming part thereof.

Fig. 1 is a plan view of a combined sole and heel; and

Fig. 2 is a side elevational view thereof, showing my new design.

Fig. 3 is a section on the line 3—3, of Fig. 1.
I claim:

The ornamental design for a combined sole and heel, as shown.

CHARLES C. ABBOTT.
